(57) **CLAIM**

The ornamental design for a telephone, substantially as shown and described.

DESCRIPTION

FIG. 1 is a perspective view of a telephone.

FIG. 2 is a front view of the telephone of FIG. 1.

FIG. 3 is a rear view of the telephone of FIG. 1.

FIG. 4 is a right side view of the telephone of FIG. 1.

FIG. 5 is a left side view of the telephone of FIG. 1.

FIG. 6 is a top view of the telephone of FIG. 1; and,

FIG. 7 is a bottom view of the telephone of FIG. 1.

The broken lines in the drawing figures that show the outermost periphery of non-claimed features represent boundaries of the claimed design. All other broken lines are directed to environment and are for illustrative purposes only. The broken lines, and the unshaded regions that are defined by broken lines, form no part of the claimed design.
